LUMINOUS PENDANT

Joseph A. Kelly, New York, N. Y., assignor to
 Luminous Processes, Inc., New York, N. Y., a
 corporation of Delaware

Application May 19, 1945, Serial No. 594,639

3 Claims. (Cl. 250—73)

1

The present invention relates to switch control pendants provided with a luminous or glowing substance, such as that commonly called radium luminous material, and, more particularly, to improved means for joining the component parts and entrapping the radium emanations.

It has been the general practice heretofore to leave one end of a radium luminous painted pendant open, thus exposing the luminous paint, or to so poorly enclose the luminous paint as to permit escape of the emanations and thereby to decrease the luminous efficiency. Furthermore, luminous painted surfaces exposed to the atmosphere are more or less rapidly coated with foreign particles, depending upon location and conditions, thereby to reduce the luminous efficiency.

Therefore, one of the objects of this invention is to completely enclose the section within the pendant, which is treated with luminous material, so that this material is sealed in to entrap the emanations.

Another object is to provide magnification of the luminosity through a section of the pendant circumscribing the luminous section, serving as a lens.

A further object is to use a clear plastic material for concentrated illumination and a milky translucent plastic material to provide an overall evenly diffused luminosity.

Still another object is to provide a pendant shaped to simulate a conventional incandescent lamp design expressive of luminosity, this same shape also utilitarian feature of providing excellent finger grip.

A still further object is to provide a pendant shaped and designed to simulate a fluorescent tube also expressive of luminosity and being convenient to the grasp.

Also, other important objects of the invention are to provide a pendant of good efficiency; simple in structure; of a nature to receive a trade-mark or insignia; long in life; pleasing in size and contour; free from liability of accidental loss of luminous paint or painted section; and easy to attach to an electric switch cord or the like.

Other and more specific objects of the invention will become apparent from a consideration of the following specification and claims in connection with the accompanying drawings illustrating the invention by way of example, in which:

Fig. 1 is an enlarged view in side elevation of a pendant embodying the invention in one of its forms;

Fig. 2 is a view similar to Fig. 1 but drawn approximately to actual size;

2

Fig. 3 is a detail view of a part of the pendant of Fig. 1;

Fig. 4 is a fragmentary partial section of a pendant embodying the invention in modified form;

Fig. 5 is an elevational view, partly in section, of a modified pendant constructed in accordance with the invention; and

Fig. 6 is a detail view of one of the parts of the pendant of Fig. 5.

The pendant 10 shown by Fig. 1 of the drawing, embodies the invention in an illustrative form and comprises an outer housing 11, which is of any suitable transparent or translucent material such as glass or plastic composition having a threaded section 12 on the small diameter end simulating a lamp base which could be brass lacquered or painted. A longitudinal hole 14 passes through the entire length, having different diameters, the smallest diameter 15 being near the top end to receive with tension the split locking cup 16 attached to the bead chain 17. The cup 16 is split, as indicated at 20, to facilitate installation. The next larger diameter 18 receives a plug 19 of plastic material or the like cemented into position. The third and fourth diameters 21 and 22 receive, cemented in place, the separate plastic or glass translucent or transparent plug 23 (Fig. 3) after having its surface 24 coated with radium luminous paint. Being of plastic the base of the plug 23 can be imprinted with an insignia, trade-mark, name, or other wording if desired. Plug 23 is provided with a center hole 28 permitting an optional method of painting the inside of the hole 28 with luminous paint, or depositing a radium active luminous powder within this hole 28 sealed into position with a cemented in plastic plug 30 (Fig. 1). A plug which is substantially the length of the bore section 22 can be used if the inside 21 of the hole within the plastic housing were itself painted with radium luminous material.

The invention shown by Fig. 1 of the drawing may be embodied in a pendant housing 35 (Fig. 4) having a small diameter section 36 to receive, clinched into position, a threaded metal cap 38 to which is fastened a bead chain 39 by means of a larger diameter split ball, for example, within the cap 38. As shown in Fig. 4, an optional split metal cup 41, split as indicated at 42, for locking the bead chain 39 within the cap 38 may be used.

The longitudinal central hole, corresponding to the hole 14 of Fig. 1, within the housing 35 does not extend throughout but is only of sufficient length to accommodate a luminous coated plug

23 cemented within the base and to provide extra length ahead of the stem of the plug to entrap the emanations.

An optional method of forming the threaded metal cap 38 is to make it of strip metal stock having an open, or rather an unjoined or butt seam down one side which flexes sufficiently to permit insertion of a small diameter pin, for example, hold the last ball of the bead chain 39. An optional method of attaching the cap 38 is to have the small diameter end 36 of outer housing 11 or 35 (Figs. 1 and 4, respectively) threaded to receive the threaded metal cap 38 threaded on and staked in position if desired to prevent accidental unthreading.

The invention shown by Fig. 5 of the drawing may be embodied in a pendant comprising an outer housing 52 which is of any suitable transparent or translucent material such as glass or plastic composition having a hole 53 running completely through to receive a glass or plastic rod 54 coated on the outside surface 54a with radium luminous material cemented and sealed in position with plastic plugs 56 (one of which appears in Fig. 5) at each end of the hole 53. Both ends 57 of the outer housing 52 are formed with an undercut 58 to receive the metal caps 59 clinched in position, the top cap having the bead chain 62 locked into position with a split washer 64 shown separately in Fig. 6.

The plastic material of the outer housings 11, 35 and 52 circumscribing the inner luminous coated sections, being convex in form, provide magnification and consequently better luminous visibility.

The invention claimed is:

1. A marking pendant for an electric switch operating cord comprising, a body composed of light-transmitting material, said body being provided with an aperture extending inwardly and axially from one of its ends, said aperture having a wide-diameter portion located adjacent to said end, a plug of light-transmitting material secured in said aperture, said plug being provided with a tubular shank portion of less diameter than the wide diameter portion of the aperture, said shank portion bearing a coating of luminescent material, an integral head formed on the

shank at one end of the same, said head being in cup-shaped form and including an annular wall portion spaced from and surrounding a portion of the luminescent-coated shank, the head having a diameter closely fitting within the wide-diameter portion of the aperture, said head having a rounded outer surface extending over one end of the shank, said surface being exposed on the outside of the body and following the curvature of adjacent surrounding portions of the body.

2. A marking pendant for an electric switch operating cord comprising, a body of light-transmitting material shaped to simulate the appearance of an electric light bulb, said body having a globular end portion, and having an axially extending bore provided with a wider-diameter portion at the end of the globular part of the body, a plug having a cylindrical head portion of a diameter enabling it to snugly fit within the wider-diameter portion of the bore, said head being of cup-shaped formation and including an annular wall, the head being provided with a central shank extending from its concave side into the bore, the periphery of the shank being surrounded for a portion of its length by the annular wall of the head but spaced from said wall, said plug being provided with a luminescent coating.

3. A marking pendant as provided for in claim 2, wherein the shank is hollow and the luminescent coating is contained on the inside of the shank, said shank being provided with a closure plug at one of its ends, said head having a rounded, outer closed end arcuately curved to follow the curvature of the globular portion of the body.
